UNITED STATES PATENT OFFICE.

LEWIS W. TILTON, OF MIAMI, FLORIDA.

BUILDING FORM.

Application filed February 9, 1921. Serial No. 443,597.

To all whom it may concern:

Be it known that I, LEWIS W. TILTON, a citizen of the United States, residing at Miami, in the county of Dade and State of Florida, have invented certain new and useful Improvements in a Building Form; and I do hereby declare the following to be a full, clear, and exact description of the invention, such as will enable others skilled in the art to which it appertains to make and use the same.

The object of the invention is to provide a simple, inexpensive and efficient means adapted to serve as a filling unit for building forms as a substitute for the wooden fillers ordinarily employed between the joists and girders in concrete and similar work in connection with building operations, and more especially to provide a unit which can be used repeatedly and for an indefinite length of time and is readily adaptable to the varying spacings to be found between the joists and other timbers in building and which for general use must be capable of adjustment in width to correspond with such spacings which are ordinarily modified in building operations to suit the purposes for which the structures are designed; and with this object in view the invention consists in a construction and combination of parts of which a preferred embodiment is shown in the drawing, wherein:

Figure 1 is an elevation of a filler unit embodying the invention arranged in the operative position with relation to joists or like building timbers, the latter being shown in cross section, and the outside form of a wall being shown fragmentarily.

Figure 2 is a detail view in perspective of the units detached.

Figure 3 is a sectional view of the device in applied position, showing fragmentarily a wall.

The device is constructed preferably of sheet metal such as steel in the form of a plate of sufficient gage to afford the necessary stability, and it preferably is constructed of sectional form to provide a plurality of members 10 and 11 adapted for arrangement in parallelism and in contact and for relative sliding movement or adjustment to vary the width of the filler, measured from the outer edge of one member to the opposite or remote edge of the other member, to correspond with the in-

tervals between the joists or other timbers in connection with which they are to be used.

In the construction illustrated the members are provided with perpendicularly disposed supporting arms 12 and 13, preferably consisting of members of angular brackets which are respectively attached to the members of the filler and are provided with perforations 14 through which nails 15 may be driven to attach the brackets, and hence the members of the filler to the flooring 15 to prevent displacement thereof during the positioning of the concrete or cement, it being preferable to drive these nails, as shown in the drawing, only a part of the way and then to bend them over as indicated so that they may readily be withdrawn when the unit is to be displaced at the completion of the operation.

One of the members of the unit is provided with a flange 16 formed by turning over or folding back one edge of the same to constitute an interlocking engagement with the corresponding edge of the other member, so as to constitute a simple means of maintaining them in their proper relative positions so far as their upper and lower edges are concerned while providing for a relative sliding movement thereof to vary the distance between their side edges to correspond with the interval between the adjacent surfaces of the joists or timbers indicated for example at 17 and between 18 which the device is positioned in lieu of the fillers ordinarily employed in concrete construction work.

The application of the invention is best shown in Figure 3 where outside and inside building forms 18 and 19 are shown and a concrete wall 20 is shown between the forms with the ends of the joists 17 extending into the wall. The filler, comprising my invention, is illustrated between a pair of adjacent joists and rests upon the upper outer edge of the inside form 19 closing the space between a pair of joists adjacent their ends.

In applying the filler the member 10 thereof may be positioned and secured by driving a nail in a perforation of the supporting arm, after which the other member may be dropped into place to interlock at its flanged edge with the corresponding edge of the first named member and after positioning the second members with its side

edge in proper relation with the surface of the adjacent joist or timber it may be secured by nails driven through a perforation of the supporting arm thereof to secure the 5 two members in cooperative relation, and it will be obvious that said operation of positioning the filler may be accomplished without loss of time and very much more expeditiously than can the ordinary wooden fillers be located in a similar relation to the joists or timbers of a building, with the additional advantage that after the concrete has been poured and allowed to set, the fillers herein described may be readily removed 10 15 and used again whereas the ordinary wooden fillers are destroyed or rendered ineffective in the removal thereof, under ordinary circumstances, so as to involve a considerable waste of timber in addition to the 20 loss of time incident to arranging the same in proper position for use.

Having thus described the invention, what I claim is:—

1. A filler unit for building forms having a sectional plate consisting of relatively movable members arranged in parallelism and provided with means for attach-

ment to the building timbers, one of the members being provided with a marginal flange having a sliding engagement with the 30 adjacent edge of the other member.

2. A filling unit for building forms comprising a plate consisting of relatively adjustable members adapted for arrangement between adjacent joists, each of said members being provided with supporting means comprising strips bent to provide angularly related arms, one of which is attached to a member comprising the unit and the other arm being perforated to provide openings 40 for fastening means.

3. A filler unit for building forms comprising a sectional plate, the sections of said plate being adjustably connected together, an attaching arm extending forwardly from each of said sections, and said attaching arms each provided with perforations adapted to receive fastening means.

In testimony whereof I affix my signature in presence of two witnesses.

LEWIS W. TILTON.
